(57) **CLAIM**

The ornamental design for a case for electronic device as shown and described.

DESCRIPTION

FIG. 1 is a front, left and bottom perspective view of a case for electronic device of our new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is top view a thereof;

FIG. 8 is a bottom view thereof;

FIG. 9 is a front perspective view thereof, showing a first stand portion of the case for electronic device in an open state and a second stand portion of the case for electronic device in a closed state; and,

FIG. 10 is a side view thereof, showing the first stand portion of the case for electronic device in a closed state and the second stand portion of the case for electronic device in an open state.

The broken lines shown in the drawings depict portions of the case for electronic device that form no part of the claimed design.
